GRIPPING, CRUSHING, OR CUTTING TOOL

Arthur John Muter, Wood Green, London, and Charles Tydeman, London, England, assignors of one-third to George Alexander Williamson, London, England

Application November 1, 1933, Serial No. 696,276
In Great Britain November 5, 1932

12 Claims. (Cl. 128—306)

The present invention relates to gripping, cutting or crushing hand tools and has for its chief object to provide an improved hand tool of this kind which is of simple constructional form and is efficient in use.

A more particular object of the present invention is to provide an improved hand tool by means of which bloodless castration i. e. bloodless crushing or severing of the spermatic cord without causing an open wound in the scrotum may be effected in an efficient manner.

With the above objects in view the present invention consists in a gripping, cutting or crushing hand tool comprising in combination a pair of jaws mounted between side plates and at least one, and preferably each of which, is adapted to be caused to slide bodily towards and away from the other by operation of a handle, pivoted about an axis constrained by the side plates to move in the direction of the longitudinal axis of the tool, through an element rotatably carried by the side plates and which is operatively engaged with a respective jaw and also pivotally connected with the handle at a distance from the pivotal axis thereof.

More specifically stated the present invention consists in a gripping, crushing or cutting hand tool comprising in combination a pair of jaws mounted for parallel sliding movement towards and away from one another between side plates and adapted to be operated by a pair of handles pivotally connected to a common axis constrained by the side plates to move in the direction of the longitudinal axis of the tool through elements rotatably carried by the side plates and each of which is operatively engaged with a respective jaw and also pivotally connected with a respective handle at a distance from the pivotal axis thereof.

In a castrating tool according to the present invention the cooperating jaw edges are preferably arranged parallel to one another and are of a rounded or blunt form so that the desired result is obtained solely by a pressing or crushing action. Means are also preferably provided which, after initial adjustment, maintain the spermatic cord in the region of action of the jaws during the castrating operation and such means desirably also automatically release the cord to permit the tool to be withdrawn readily upon completion of the operation.

In order that the invention may be more clearly understood and readily carried into effect reference may now be had to the accompanying drawings illustrating the invention by way of example and in which:

Fig. 1 is a partial elevation view of a castrating tool according to the present invention with the parts in the positions which they occupy just prior to the commencement of the castrating operation;

Fig. 2 is a view similar to that of Fig. 1 with the parts in the positions they occupy at the completion of the castrating operation;

Fig. 3 is a side elevational view of the tool as shown in Fig. 2;

Fig. 4 is an elevational view of the tool as shown in Fig. 2 with one of the side plates and the spermatic cord holding and retaining means removed;

Fig. 5 is a view similar to Fig. 4 showing the jaws open;

Fig. 6 is a view similar to Fig. 4 of a modified form of tool;

Figs. 7 and 8 illustrate a modified form of operative engagement between the rotatable element and the jaw;

Figs. 9 and 10 illustrate a further modified form of operative engagement between the rotatable element and the jaw; and

Figs. 11 and 12 illustrate in front and side elevation respectively one means by which wear may be taken up in a tool as illustrated in Figs. 1—5.

Referring first to Figs. 1—5 the castrating tool shown comprises a pair of jaws 1 adapted for sliding movement towards and away from one another between side plates 4. For this purpose each jaw may be provided near its base with laterally projecting tongues 2 which slidably engage in grooves or slots 3 in the side plates 4. Alternatively the jaws may be grooved or slotted to accommodate inward projections in the side plates. The side plates 4 are firmly connected together by screws or rivets 4a. Owing to the slidable engagement of the jaws 1 with the side plates 4, the jaws 1 may be readily detached by suitably proportioning the tool so as to permit rotatable elements 5 hereinafter described to be moved out of engagement therewith. Normally however means are provided to prevent sliding movement of the jaws to this extent.

Mounted between the side plates 4 are elements 5 which are rotatable upon pivots 6 carried by the plates 4 and each element is operatively engaged but not positively connected with a respective one of the jaws 1 at one end and is pivotally connected as at 7 at its other end to a handle 8. The handles 8 are themselves mounted for pivotal movement about a common pin 9—distant from the pivotal connections 7—the ends of which are guided for movement in

the direction of the longitudinal axis of the tool in slots 10 in the side plates 4.

As shown in Figs. 1-5 the base of each jaw is specially formed for cooperation with a corresponding formation on the associated element 5 so that as the element 5 is rocked to and fro around its pivot the jaw will slide backwards and forwards between the side plates 4.

With the construction described the pivotal connections 7 are free to move laterally of the tool as viewed in Figs. 1, 2, 3 and 5 and the pin 9 is constrained to move in the direction of the longitudinal axis of the tool by the slots 10 whilst the pivots 6 are stationary. Preferably the parts of the tool are so designed that when the edges of the jaws are just touching, the axis of the pin 9 is just below a line joining the axes of the pivotal connections 7 as this ensures that further upward movement of the pin 9 results in considerable pressure being exerted at the jaws.

For the purpose of initially positioning and maintaining the spermatic cord in the region of action of the jaws during the castrating operation a pair of arms or elements 11 are pivotally mounted at 12 on one of the side plates 4 and each arm or element 11 has a portion 13, on one side of the pivot, which extends adjacent one of the jaws and a portion 14, on the other side of the pivot, extending adjacent the jaw operating means. The portions 13 of the arms or elements 11 are shaped or formed—for example by being curved at the outer end as shown—in such wise as to provide in one position of adjustment—as shown in Fig. 1—an enclosure 15 within which the spermatic cord is confined. The portions 14 of the arms or elements 11 are adapted for cooperation with a cam device 16 carried by the movable pin 9 and which is shaped so that when adjusted to the position shown in Fig. 1 by manipulation of the lever 17 attached to it and the end of which is guided in a slot 18 in one of the side plates 4, it will press the portions 14 of the arms 11 apart against the action of springs 19 acting on the other side of the pivot 12 and maintain the enclosure 15 closed. As the pin 9 moves in the direction of the longitudinal axis of the tool due to operation of the handles 8 for the purpose of closing of the jaws 1 the cam device 16 will be carried by it and the sides of the portions 14 of the arms or elements 11 are so shaped that during the greater part of this movement the enclosure 15 is maintained closed, it being understood that the cam device 16 is maintained in the position shown in Fig. 1 during this movement by cooperation of the end of the lever 17 with the slot 18. However, at the completion of the castrating operation one end of the cam device 16 moves into a recess or enlargement 20 formed in one of the arms or elements 11 and due to the action of the springs 19 the cam device is turned and the arms or elements 11 moved into the position shown in Fig. 2, thereby opening the enclosure 15 and permitting the tool to be removed. It will be understood that at the time the cam device 16 enters the recess or enlargement 20 the end of the lever 17 also comes opposite a recess in the wall of the slot 18 which permits the lever to move to the position shown in Fig. 2.

In the use of a tool as described, assuming its parts to be in the position shown in Fig. 2, the ends of the handles 8 are first moved away from one another thereby causing the pin 9 to move downwardly in the slots 10 and the pivotal connections 7 to move inwardly or towards one an-

other with the result that the elements 5 are rotated on their pivots 6 in opposite directions and due to their operative connection with the jaws 1 the latter are moved away from one another to the positions shown for example in Figs. 1 and 5.

The lever 17 is then moved to rotate the cam device 16 clockwise and its end is engaged in the slot 18. This has the effect of rotating the arms or elements 11 in opposite directions to form the enclosure 15 and retain the spermatic cord in the region of action of the jaws. At this stage the parts of the tool occupy the positions shown in Fig. 1.

The ends of the handles 8 are then moved inwardly or towards one another thereby causing the pin 9 to move in the reverse direction in the slots 10 and each of the elements 5 to be rotated on its pivot 6 in a direction opposite to that in which it was rotated during outward movement of the ends of the handles, with the result that the jaws are closed and the spermatic cord squeezed or pressed between their operating edges.

At the completion of the operation the cam device 16 is adapted to move into the recess or enlarged portion 20 and the arms or elements 11 are rocked in opposite directions by the springs 19 to open the enclosure 15 and permit withdrawal of the tool, the necessary anticlockwise movement of the lever 17 being permitted due to the beforementioned recess in the wall of the slot 18.

The effect of guiding the ends of the pin 9 in the slots 10 is to distribute more evenly the pressure derived from the handles 8 on the elements 5 and consequently on the jaws 1.

While the hereinbefore described form of operative engagement between the jaws 1 and elements 5 has been found satisfactory in practice any other suitable form may be employed for example in the modified form of tool shown in Fig. 6 each jaw is formed or provided at its base with a toothed rack 21 and each element 5 is formed or provided with a toothed segment 22 adapted to cooperate with the respective toothed rack 21. Alternatively in Figs. 7 to 10 inclusive a cam and slot form of operative engagement is employed, Figs. 7 and 8 showing a cam element 23 formed integrally with a rotatable element 5 and cooperating with a suitable slot 24 formed in the base of the jaw and Figs. 9 and 10 showing a slightly modified construction in which substantially a spherical member 25 adapted to cooperate with a similarly shaped recess 26 in the base of the jaw has a pin or shank 27 which engages in a slot 28 in the element 5. In Figs. 7 and 8 the arrows show the direction of rotation of the cam necessary to close and open the jaw respectively. As will be appreciated where a cam and slot form of operative engagement is employed, instead of the cam being associated with the element 5 and the slot with the jaw, the cam may be associated with the jaw and the slot with the element 5.

In the continual use of a tool as described it is found that after a time wear develops between the jaws and rotatable elements and means may be provided to enable such wear to be taken up readily. For this purpose in a tool having a form of operative engagement between each jaw and its cooperating rotatable element as shown in Figs. 1-5 each element 5 may be provided with an adjusting screw 29 which is operable by a key or the like from the side of the tool as shown in

Figs. 11 and 12 whereby backlash may be prevented and the parts maintained in such relation that movement of the appropriate handle 8 results at once in corresponding movement of the 5 associated jaw 1.

As the tool so far described is intended primarily for castration purposes the jaws are shown as having blunt or rounded crushing edges but when the tool is used for other purposes other 10 types of jaws may be used or substituted for those shown. For example for cutting purposes jaws having more or less sharp cutting edges are used. Moreover if desired the edges of the jaws may be detachable thereby enabling the tool to be 15 adapted for a particular use merely by equipping the jaws with appropriate edges. As will be understood the jaws may be straight curved or angular according to the purpose for which the tool 20 is to be used and instead of both jaws being movable one may be stationary and the other movable.

Owing to the improved construction of the tool it is found that it is possible to obtain great power at the jaws and due to the jaws and 25 the operating means of a tool as shown all lying in substantially the same plane such a tool is found to be of special use for castration purposes as it enables easy access to be had to the spermatic cord from practically any angle.

30 What we claim is:—

1. A hand tool comprising in combination, a pair of side plates, a pair of jaws at least one of which is bodily slidable towards and away from the other mounted between said side plates, a handle for operating each slidable jaw pivoted about a pin constrained by the side plates to move in the direction of the longitudinal axis of the tool, a rotatable element associated with each slidable jaw and operatively engaged therewith, and pivot means connecting each said element to an appropriate handle at a distance from said pin.

2. A hand tool as claimed in claim 1 in which 45 said pin is constrained to move in the direction of the longitudinal axis of the tool by engagement of its opposite ends in slots in said side plates.

3. A hand tool comprising in combination, a pair of side plates, a pair of jaws mounted for parallel sliding movement towards and away from one another between said side plates, a pair 50 of handles, a pair of elements each rotatably mounted between said side plates and each operatively engaged with a respective one of said jaws, pivot means connecting each said element to a respective one of said handles, and a common pivot pin, constrained to move in the direction of the longitudinal axis of the tool, connecting said handles and adapted to lie to one side of a plane passing through said pivot means when said jaws are just engaged so that further movement of said pin towards said plane will cause considerable pressure at said jaws.

4. A hand tool as claimed in claim 3 in which 55 said pin is constrained to move in the direction of the longitudinal axis of the tool by engagement of its opposite ends in slots in the side plates.

5. A castrating tool comprising in combination, a pair of side plates, a pair of jaws at least one of which is bodily slidable towards and away from the other mounted between said side plates, a handle for operating each movable jaw pivoted

about a pin constrained to move in the direction of the longitudinal axis of the tool, an element rotatably carried by said side plates associated with each slidable jaw and operatively engaged therewith, pivot means connecting each said element to the appropriate handle at a distance from said pin, and means the operation of which is governed by the position of said pin for positively retaining the spermatic cord in operative relation to the jaws during the castrating operation. 10

6. A castrating tool as claimed in claim 5 in which said last mentioned means automatically release the spermatic cord and permit withdrawal of the tool upon completion of the castrating 15 operation.

7. A castrating tool comprising in combination, a pair of side plates, a pair of jaws mounted for parallel sliding movement towards and away from one another between said side plates, a pair of 20 handles, a pair of elements each rotatably mounted between said side plates and each operatively engaged with a respective one of said jaws, pivot means connecting each said element to a respective handle, a common pivot pin, constrained to move in the direction of the longitudinal axis of the tool, connecting said handles and adapted to lie to one side of a plane passing through said pivot means when said jaws are just 25 in engagement, so that further movement of said pin towards said plane will cause considerable pressure at said jaws, and means the operation of which is governed by the position of said pin for positively retaining the spermatic cord in operative relation to the jaws during the castrating 30 operation. 35

8. A castrating tool as claimed in claim 7 in which said last mentioned means automatically release the spermatic cord and permit withdrawal of the tool upon completion of the cas- 40 trating operation.

9. A castrating tool comprising in combination, a pair of side plates, a pair of jaws at least one of which is bodily slidable towards and away from the other mounted between said side plates, a 45 handle for operating said slidable jaw pivoted about a pin constrained to move in the direction of the longitudinal axis of the tool, an element associated with each slidable jaw rotatably mounted between said side plates and operatively 50 engaged with said jaw, pivot means connecting each said element to the appropriate handle at a distance from said pin, a pair of arms pivoted about a second common pin and extending on one side of said common axis adjacent said jaw and 55 on the other side of said common axis adjacent said jaw operating means, and a cam device carried by said first pin and cooperating with said arms in such a manner that during closing of the jaws the spermatic cord is retained by said arms 60 in the region of action of said jaws.

10. A castrating tool comprising in combination, a pair of side plates, a pair of jaws mounted for parallel sliding movement towards and away from one another between said side plates, a pair 65 of handles, a pair of elements each rotatably mounted between said side plates and each operatively engaged with a respective jaw, pivot means connecting each said element to a respective handle, a common pivot pin, constrained to move in the direction of the longitudinal axis of the tool, connecting said handles and adapted to lie at one side of a plane passing through said pivot means when said jaws are just in engagement, so that 70 75

further movement of said pin towards said plane will cause considerable pressure at said jaws, a pair of arms pivoted about a second common pin and extending on one side of said second common 5 pin adjacent said jaws and on the other side of said second common pin adjacent the jaw operating means, and a cam device carried by the first mentioned common pin and cooperating with said arms in such a manner that during closing of the 10 jaws the spermatic cord is retained by the arms in the region of action of said jaws.

11. A castrating tool comprising in combination, a pair of side plates, a pair of jaws at least one of which is bodily slideable towards and away 15 from the other mounted between said side plates, a handle for operating each slideable jaw pivoted about a pin constrained by the side plates to move in the direction of the longitudinal axis of the tool, a rotatable element associated with each 20 slideable jaw and operatively engaged therewith, pivot means connecting each said element to the appropriate handle at a distance from said pin, and means for positively retaining the spermatic

cord in operative relation to the jaws during the castrating operation.

12. A castrating tool comprising in combination, a pair of side plates, a pair of jaws mounted for parallel sliding movement towards and away 5 from one another between said side plates, a pair of handles, a pair of elements each rotatably mounted between said side plates and each operatively engaged with a respective one of said jaws, pivot means connecting each said element to a 10 respective one of said handles, a common pivot pin, constrained to move in the direction of the longitudinal axis of the tool, connecting said handles and adapted to lie at one side of a plane passing through said pivot means when said jaws are 15 just in engagement so that further movement of said pin towards said plane will cause considerable pressure at said jaws, and means for positively retaining the spermatic cord in operative relation to the jaws during the castrating 20 operation.

ARTHUR JOHN MUTER.
CHARLES TYDEMAN.
